UNITED STATES PATENT OFFICE

112,149

DESIGN FOR A DISPLAY CASE

Paul M. Kleinwachter, Chicago, Ill.

Application March 24, 1938, Serial No. 76,067

Term of patent 14 years

To all whom it may concern:

Be it known that I, Paul M. Kleinwachter, a citizen of the United States, residing at Chicago, in the county of Cook and State of Illinois, have invented a new, original, and ornamental Design for a Display Case, of which the following is a specification, reference being had to the accompanying drawing, forming a part thereof.

Fig. 1 is a front perspective view and Fig. 2 is a reduced scale rear perspective view of a display case, showing my new design.

I claim:

The ornamental design for a display case, substantially as shown.

PAUL M. KLEINWACHTER.
